UNITED STATES PATENT OFFICE.

BRUTUS A. McGEE, OF CHICAGO, ILLINOIS.

NURSING-BOTTLE SUPPORT.

1,276,936.

Specification of Letters Patent. Patented Aug. 27, 1918.

Application filed June 27, 1917. Serial No. 177,184.

To all whom it may concern:

Be it known that I, BRUTUS A. McGEE, a citizen of the United States, residing at Chicago, in the county of Cook and State 5 of Illinois, have invented a certain new and useful Improvement in Nursing-Bottle Supports, of which the following is a specification.

My invention relates to nursing bottle supports, that is devices intended to hold a 10 baby's nursing bottle in proper position for use at all times so as to obviate the difficulties which ensue from the momentary disengagement of the baby from the bottle in 15 the absence of the attendant.

My invention is illustrated more or less diagrammatically in the accompanying drawings, wherein—

Figure 1 is a side elevation of a support 20 with the bottle in position;

Fig. 2 is a section on the line 2—2 of Fig. 1 with the bottle removed;

Fig. 3 is a view of a modification of the parts shown in Fig. 2;

Fig. 4 is a detail of a modification of the 25 front portion of the support;

Fig. 5 is a view of a two part front support;

Fig. 6 is an elevation of a modification of 30 the front support;

Fig. 7 is a cross section on the line 7—7 of Fig. 6;

Fig. 8 is a side elevation of a modification; 35

Fig. 9 is a plan view thereof; and

Fig. 10 is a cross section on the line 10—10 of Fig. 8.

Like parts are indicated by like letters in 40 all the figures.

A is a base plate on which is mounted the supporting ends B and C. The supporting end B is provided with a notch in its upper part in which lies the rear end of the bottle D. The supporting end C is preferably provided with an aperture C¹ which receives the narrowed neck or other narrowed portion of the bottle. E, the nipple associated with the bottle, projects beyond the supporting end C. Either or both of the 45 ends C and B may be hinged to the base at F but either or both such hinges may be dispensed with. The supporting end C may have a notch C² instead of an opening as indicated in Fig. 3 and the bottle may be held

down into position by the securing piece G 55 or wires, string, elastic or other material sprung in place or secured in any desired manner. Obviously the supporting end B could be supplied with a hole instead of a notch if that were desired. An essential 60 point is that the bottle be supported in inclined position so that its contents will tend to flow toward the nipple. As illustrated in Figs. 4 and 5 the end support C is rigid with the base A and associated with a hinged 65 or movable support J in this case preferably of wire and arranged to form a loop or opening J¹ smaller than the opening C¹ so as to adapt the device for two sizes of bottles. The wire J makes an elastic 70 opening J¹ so as to make the device adaptable for bottles of various sizes.

In the event of the use of a bottle of uniform diameter the forward end of the bottle is commonly associated with some annular protuberance which may hold the bottle in position in the opening or notch. In such cases the bottle may be securely clamped into position by an elastic holder like that illustrated in Fig. 5 or by use of the 80 elastic securing piece illustrated in Fig. 3.

In Figs. 6 and 7 I have illustrated means whereby the device may be adapted to hold the bottle at different inclinations. In this case the base A has at its forward end two 85 standards K K. I also provide a sliding plate L having toward one end the opening M. The standards and the plate are associated by means of the tongue and groove so that the plate can slide on the standards 90 and by taking it out and reversing it the relative altitude of the opening may be varied so as to vary the inclination of the bottle.

In Figs. 8, 9 and 10 is illustrated a swivel 95 device particularly adapted to hold a bottle of uniform cross section.

P is the base from which rises the pivot lug P¹ adapted to receive the pin P² on the projection P³ of the carrying lug P⁴. This 100 lug is inclined and grooved at P⁵ to receive the bottle P⁶. The bottle is preferably held in position by the clamps P⁷ P⁷ which may be made of any desired material as for instance rubber.

The holes R R in the base are intended to afford means for tying or screwing or holding the base down when that becomes

necessary. The larger center hole C is intended simply to lighten the base by reducing the amount of material.

It will be understood that my drawings 3 are to be taken as diagrammatic though they do illustrate actual working structures. The parts may, of course, be greatly altered in size, proportion and arrangement without departing from the spirit of my invention and I wish, therefore, that my drawings may be taken as diagrammatic and intended only to illustrate the idea rather than to display or limit me to any particular form of structure. The materials used 15 may be as desired of wood, metal, fiber, celluloid or anything else suitable. Some or all of the several features here shown can be incorporated in a single structure. The bottle supporting parts illustrated in any 20 of the figures could be mounted pivotally on the base and the two front and rear supporting ends can be formed as indicated in Fig. 8 as sections of a single continuous piece or body.

35 The use and operation of my invention are as follows:—

When the nipple of the nursing bottle slips from the baby's mouth and the baby tries to recover it the bottle of course has 30 assumed another position or has rolled away from the baby and the result is that the baby is helpless until relieved by the attendant. With my invention the bottle is held at all times in the same general position which it assumes when the baby is 35 using it and hence when the baby returns, as he instinctively does, to the position where he last had the bottle he finds the nipple in proximity to his mouth. The device can be tied down by means of the holes 40 in the base or it can be fastened down in permanent position or it can be mounted

upon a relatively heavy and fixed base so as to swivel or have a horizontal motion about the pivot.

I claim:

1. A nursing bottle support comprising a base, a cradle consisting of folding end supports mounted on the base and adapted to support the bottle in an inclined position, 50 and means for holding the bottle from longitudinal movement on the cradle.

2. A nursing bottle support comprising a base, a cradle consisting of folding end supports mounted on the base and adapted to support the bottle in an inclined position, 55 and means for holding the bottle from longitudinal movement on the cradle, said means associated with the forward support.

3. A nursing bottle support comprising a 60 relatively flat and extended base with a front support having a hole therethrough smaller than the cross section of the bottle body, a rear support on the base having a notch in which the lower end of the body 65 rests, and a secondary forward support having an opening of a different size from the opening of the primary forward support.

4. A nursing bottle support comprising a 70 relatively flat and extended base with a front support having a hole therethrough smaller than the cross section of the bottle body, a rear support on the base having a notch in which the lower end of the body 75 rests, and means for varying the altitude of the opening in the forward support.

In testimony whereof, I affix my signature in the presence of two witnesses this 18th day of June 1917.

BRUTUS A. McGEE.
